(57) CLAIM

The ornamental design for a protective casing with integral bumper for an electronic communications device, as shown and described.

DESCRIPTION

FIG. 1 is a left side view of the protective casing with integral bumper for an electronic communications device; FIG. 2 is a top view of the protective casing with integral bumper for an electronic communications device; FIG. 3 is a bottom view of the protective casing with integral bumper for an electronic communications device; FIG. 4 is a back view of the protective casing with integral bumper for an electronic communications device; and, FIG. 5 is a front perspective view of the protective casing with integral bumper for an electronic communications device.

The broken lines represent a boundary of the claimed design. The surface area inside the boundary forms no part of the claimed design.
